GEORGE B. THOMAS, OF BRIDGEPORT, CONNECTICUT, ASSIGNOR TO THE PERKINS ELECTRIC SWITCH MANUFACTURING COMPANY, OF BRIDGEPORT, CONNECTICUT, A CORPORATION OF CONNECTICUT.

ELECTRIC SWITCH.

1,161,752.

Specification of Letters Patent. Patented Nov. 23, 1915.

Application filed April 8, 1914. Serial No. 830,492.

To all whom it may concern:

Be it known that I, GEORGE B. THOMAS, a citizen of the United States of America, and residing at Bridgeport, in the county of 5 Fairfield and State of Connecticut, have invented a certain new and useful Improvement in Electric Switches, of which the following is a specification.

My invention relates to electric switches 10 and particularly to snap switches, and the object of my invention is to provide a switch which may be used to advantage as a starting switch for motors, especially where it is desirable to introduce the current gradually 15 to the motor through resistance.

In the accompanying drawings, Figure 1 is a vertical section through a switch in which my invention is embodied in one form; Fig. 2 is a detached perspective of the 20 switch spindle elements; Fig. 3 is a plan of the switch cover; Fig. 4 is a similar view of the indicating dial; Figs. 5 to 8 are diagrammatic plans showing the positions of the switch blades in "off," "1" "2" and "on" 25 positions respectively; and Fig. 9 is a diagram of the connections from the line wires through the switch to the load.

The switch here shown comprises a base 10 of porcelain or other suitable insulating 30 material provided with four combined wire and switch terminals 11, 12, 13 and 14. Two of the switch terminals 11 and 12 are arranged at one level to coöperate with the switch blade 15. The other pair 13 and 14 35 (not shown in Fig. 1) are arranged at a higher level in the well understood manner employed in double pole switches, to coöperate with the upper switch blade 16. This upper blade 16 is carried by a yoke 17 40 rigid with the switch spindle 18 and here shown soldered thereto at 19, together with the crown 20. The downwardly extended fingers of the latter serve as abutments for the upper end of the coil spring 21 which 45 surrounds the spindle and engages at its lower end one of the rivets 22 which connect switch blade 15 to the yoke 23. A pair of lugs 24 (only one of which is shown) on the yoke straddle, in well understood manner, 50 the arm 25 of the stop plate 26 which is centrally apertured to afford a bearing for the cam 27 clamped in the notch 28 of the spindle. The downwardly angled finger 29 on arm 25 engages the several shoulders of the

ratchet plate 30 pinned to the plate 31 which 55 is set into the base 10 and held against rotation in any suitable manner. A washer 32 engaging the notch 33 in the lower end of the spindle below the web 34 of the base, holds the spindle and parts assembled 60 against withdrawal.

The ratchet plate 30 is of peculiar form, having not only the four usual shoulders *a*, *b*, *c* and *d* arranged at angles of 90° apart, but also additional shoulders *e* and *f* diametrically opposite each other and spaced 65 equidistant between shoulders *a* and *b* on the one side and shoulders *c* and *d* on the other side. The function of these supplemental stops will be presently pointed out. 70

The switch is provided also with a cover 35 having in its upper face two sight apertures 36 and 37 cut at different radial distances from and on opposite sides of the axis of the switch. Immediately beneath the 75 cover is a dial 38 rigid with the switch spindle 18 and having on concentric circles indications of the switch position. Thus in the outer circle which registers with aperture 37 in the cover, the numerals 1 and 2 are arranged at predetermined intervals, while on the inner circle which registers with aperture 36 in the cover, the words "On" and 80 "Off" appear spaced properly apart.

The switch may be connected up as in 85 Fig. 9, one of the mains, viz. 39 being directly connected to one of the load wires, viz., 41. The other main 40 is connected to two terminals 11 and 14 of the switch, while the coöperating switch terminals 12 and 13 90 are connected to the load wire 42, the lead from 12 being direct, whereas the lead from 13 is through a resistance R.

The operation of the switch is as follows:—Assuming the blades to be in the position shown in Fig. 5, the switch is "off" 95 with the switch blade 15 underlying the raised switch terminals 13 and 14. If the switch spindle 18 is now rotated in the usual direction (see arrow Fig. 5) by means of 100 the thumb key 43 not only is the switch blade 16 carried around with the spindle into position to engage the terminals 13 and 14 but the switch spring 21 is also placed under tension while at the same time the stop lug 105 29 is moved outward along the face of shoulder *d* or *b* of the ratchet plate. When the blade 16 has reached its full contact position

(Fig. 6), the numeral "1" on the dial 38 appears below aperture 37 in the cover, the stop finger 29 has escaped the shoulder *d* or *b* and impinged upon shoulder *e* or *f* carrying switch blade 15 to the position shown in Fig. 6. This rotation of blade 15 serves merely to partially relieve the spring 21 of its tension. Consequently if the thumb piece 43 were released, the blade 16 would be rotated backward and the connection between terminals 14 and 13 broken. This connection, which leads through the resistance *R* is intended to be merely temporary until the motor is under way. The operator therefore must hold the switch at this point for a few moments, whereupon, the motor having been now well started, the full current may be turned on and the motor speeded up, by rotating the switch spindle in the direction of the arrow until the numeral "2" appears beneath the aperture 37 in the cover. This frees the stop 29 from the shoulder *e* or *f* and the switch blade 15 is thereupon rotated until stop 29 engages shoulder *a* or *c* in which position the blade 15 connects terminals 11 and 12 and the resistance *R* between the main and the motor is short circuited. When the thumb piece 43 is now released, the tension of the spring 21 is sufficient to force it past its contacts 13 and 14 to the position shown in Fig. 8, thus leaving the connection solely through the blade 15. In this position of rest the word "On" appears at the aperture 36 in the cover. To return to the "off" position the spindle is rotated in the usual manner until the finger 29 escapes shoulder *a* or *c* of the ratchet plate, whereupon the switch blade 15 is rotated through an angle of 90° to position beneath the terminals 13 and 14, since there are no stop shoulders such as *e* and *f* intermediate shoulders *a* and *d* on the one hand, or *c* and *b* on the other hand. The blade 16 also takes the position shown in Fig. 1 and the word "Off" appears on the dial beneath the aperture 36 in the cover.

It will be recognized that while the base and combined wire and switch terminals have a form commonly found in double pole switches and a pair of switch blades coöperating with these terminals is provided, yet the device is in reality a combination of two single pole switches each blade acting independently of and alternatively to the other. Again, it will be noted that while the blade 15 carried by the yoke 23 is controlled by the escapement mechanism and has a snap make and break action (which is important because it governs the full current) yet blade 15, which controls the resistance shunt, has neither snap make nor break, but moves with the switch spindle as the thumb key is rotated by hand or in the reverse direction by the spring 21.

Various modifications of the construction

will readily suggest themselves and I do not limit myself to the details shown.

I claim as my invention:—

1. In an electric switch, two pairs of switch terminals of like polarity, two double break switch blades coöperating therewith, and means for establishing connection through the switch, first through one switch plate and then through the other, substantially as described. 75

2. In an electric switch, two pairs of switch terminals of like polarity, two double-break switch blades coöperating therewith, and means for establishing connection through the switch, first through one switch plate and then through the other, only one of said switch blades making and breaking contact with the switch terminals with a snap action. 80

3. In an electric switch, independent switch terminals, independent switch blades coöperating therewith, a switch spindle common to said switch blades, one of said blades moving with the spindle and the other having an escapement control actuated by said spindle. 85

4. In an electric switch, an actuating spindle, a switch blade moving therewith, an independent switch blade, an escapement mechanism therefor and means for actuating said mechanism from the switch spindle. 95

5. In an electric switch, an actuating spindle, a switch blade moving therewith, an independent switch blade journaled on said spindle, an escapement mechanism for said blade comprising a spring operatively connected at one end to the spindle and at its other end to said escapement controlled blade, and independent switch terminals for said respective blades, the blade moving with the switch spindle making contact while the escapement spring is still under tension and in advance of the contact made by the escapement controlled blade, substantially as described. 100

6. In an electric snap switch, an escapement mechanism comprising a ratchet plate having four stop shoulders spaced 90° apart and a pair of diametrically opposite auxiliary stop shoulders arranged midway between opposite pairs of said first mentioned shoulders, for the purpose described. 110

7. An electric switch having a switch spindle, two independent single pole double break switch blades thereon, switch terminals therefor, and means for bringing said blades into engagement with the switch terminals serially, substantially as described. 120

8. An electric switch having a switch spindle, two independent single pole double make switch blades thereon, switch terminals therefor, and means for bringing said blades into engagement with the switch terminals serially, only one of said blades having a snap action, substantially as described. 125

9. In a motor starting switch, switch ter- 130

minals for shunt resistance connection between main and motor circuit, and switch terminals for a direct connection between the main and motor circuit, independent rotary
5 switch blades coöperating with said terminals, and a snap switch escapement mechanism controlling only the make and break of the blade making the direct connection.

In testimony whereof I have signed my name to this specification in the presence of 10 two subscribing witnesses.

GEORGE B. THOMAS.
